Inventor

E.R. Carson,

By *Clarence A. O'Brien*, Attorney

UNITED STATES PATENT OFFICE.

ERNEST RICHARD CARSON, OF DENVER, COLORADO.

PNEUMATIC-TIRE PUMP.

Application filed December 17, 1926. Serial No. 155,456.

This invention relates to an improved air pump for automobile tires and the like.

My principal aim is to generally improve upon structures of this class by providing one embodying a novel arrangement of details, serving to produce an improved structure characterized by durability, powerful leverage, speed in operation, and simplicity and inexpensiveness of manufacture.

10 Briefly, the invention comprises a base having a special standard made up of a pair of vertical frames between which is a slide in which a cross head is slidably mounted. A linkage structure is connected with this 15 cross head and pivotally connected with the standard and serves to operate a dual arrangement of small pumps associated directly with the linkage, the cross head being operated by a reciprocating operating rod of somewhat conventional design.

20 The specific details will become apparent from the following description and drawings.

In the drawings:—

25 Figure 1 is a side view of a pump constructed in accordance with the present invention.

Fig. 2 is a horizontal section on the line 2—2 of Fig. 1, looking downwardly, and

30 Fig. 3 is a cross section taken approximately upon the plane of the line 3—3 of Fig. 1.

35 Referring now to the drawings in detail, it will be seen that the reference character 1 designates a base from which the standard 2 rises. This standard is actually made up of a pair of vertically extending frames 3 having suitably located cross-braces 4. Of course, the respective frames may be connected together, so that they may be maintained in proper spaced relationship.

40 Located between these frames is a vertically guide track 5 upon which a cross head 6 is slidably mounted. This head is operated by a slidably mounted rod 7 having a suitable handle 8 at its top. The rod is mounted of course upon the standard in any appropriate manner.

45 As before stated, a novel linkage structure is employed for imparting movement to the miniature pumps 9. There are two of these pumps each including a cylinder 10 and a piston 11. The linkage structure for operating the pumps comprises an upper set 12 of links, and a lower set 13. Each set is actually composed of two pairs of links, the

links of each pair being represented by reference characters 14. The links are disposed in diverging relation, the links of the upper and lower pairs being pivotally connected together as at 15.

The lower ends of the lower set of links is pivotally connected to a cross piece 16 on the lower end portions of the standards, while the upper ends of the upper links are pivotally connected with the slide or head 6. In addition, the cylinders 10 are pivotally mounted as at 17 upon the lower links, while the piston rods are pivotally connected to pins 18 carried by the upper links.

45 Discharge hoses 19 lead from the discharge ends of the cylinders and connect through a coupling 20 with the main discharge hose 21 which carries the tire valve coupling (not shown).

50 Obviously, as the operating rod 7 is reciprocated in the ordinary manner, the linkage structure serves to operate the pumps due to the expansion and contraction of the various links. In this way, the air is forced under pressure into the tire. The quantity of air is substantially doubled and the leverage is such as to be multiplied by the presence of the linkage and to render the operation of the links comparatively easy.

55 It is believed that by considering the detailed description in connection with the drawings, a clear understanding of the invention as well as the operation of the advantages will be had. Therefore, a more lengthy description is thought unnecessary.

While the preferred embodiment of the invention has been shown and described, it is to be understood that minor changes coming within the field of invention claimed may be resorted to if desired.

Having thus described my invention, what I claim as new is:—

1. In an air pump of the class described, a base, a standard rising from said base, said standard being composed of a pair of vertically extending spaced parallel frames, a guide track extending vertically between said frames and connected thereto, a slide mounted upon said track, an operating rod for said slide, a handle carried by said rod, a pump including a cylinder and a piston slidable therein, an operating connection for said pump connected with said slide, said operating connection comprising leverage multiplying linkage connected with said slide and with said pump.

2. In a tire pump structure of the class described, a base, a standard rising from said base, a guide track associated with said standard, a slide mounted on said guide track, an operating rod for said slide, a handle for said operating rod, a dual arrangement of pumps, and operating linkage for said pumps, certain of the links being pivotally connected with said standard, and 10 others of the links being connected with said slide.

3. In a tire pump of the class described, a base, a standard rising from the base and embodying a pair of spaced parallel vertically extending frames connected together, a vertical guide located between said frames, a slide mounted in said guide, an operating

rod slidably mounted upon the standard and connected with said slide and the like, a handle for said rod, air pumps, each including a cylinder and the piston slidable in the cylinder, operating linkage for said pumps, said linkage comprising upper and lower sets of links, each set being composed of two pairs of links, the upper ends of the upper set being pivotally connected to said slide, the lower ends of the lower set being pivotally connected to said standard, and the adjacent ends of the respective sets being pivotally connected together, and pivotal connections between the pump pistons, cylinders, and links.

In testimony whereof I affix my signature.
ERNEST RICHARD CARSON.
